UNITED STATES PATENT OFFICE.

JOSEPH CUSHING, OF OMEMEE, NORTH DAKOTA, ASSIGNOR TO JOHN SULLIVAN, OF GRAND FORK, BRITISH COLUMBIA.

DRILL.

No. 832,779.

Specification of Letters Patent.

Patented Oct. 9, 1906.

Application filed November 19, 1904. Serial No. 233,526.

To all whom it may concern:

Be it known that I, JOSEPH CUSHING, a subject of the King of England, residing at Omemee, in the county of Bottineau and State of North Dakota, have invented a new and useful Drill, of which the following is a specification.

This invention relates generally to drills, and particularly to one adapted for use either in drilling wells or for mining purposes.

The object of the invention is to present a thoroughly efficient and durable drill in the use of which rapid cutting away of the material upon which it is operating may be effected and in which sharpening of the drill when blunt is greatly facilitated and repairs when necessary are expedited.

With the above and other objects in view, as will appear as the nature of the invention is better understood, the same consists in the novel construction and combination of parts of a drill, as will be hereinafter fully described and claimed.

In the accompanying drawings, forming a part of this specification, and in which like characters of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in vertical section through a drill constructed in accordance with the present invention, showing the assembling-band or means for holding the drill-sections combined and also a portion of a drill combined with the assembling-band. Fig. 2 is a view in elevation of the cutting end of the drill. Fig. 3 is a perspective detail view of one of the drill members. Fig. 4 is a perspective detail view of a portion of one of the drill members.

The drill, as shown in Fig. 1, is composed of a plurality of members 4, of which there may be any desired number, each member being provided at one end with a chisel cutting edge 5, and at its other end, on its outer face, with threads 6, that are disposed below the plane of the face for a purpose that will presently appear.

Each of the drill members is approximately keystone-shaped in cross-section, with the outer face rounded, so that when the members are assembled, as shown in Fig. 2, a drill that is circular in cross-section will be produced. When the members are combined to present a drill, the juncture between the meeting faces thereof will be such as to preclude entrance of any material therebetween that would operate to force the members apart, and thus increase the diameter of the drill, and in this instance the assembling is secured through the medium of a band 7, which is internally threaded to engage with the threaded portions 6 of the drill members, the diameter of the band being the same as that of the drill, so that when in position, as shown in Fig. 1, it will, in effect, constitute a continuation of the drill and will not present an obstruction that would tend to retard its operation. The band-assembling device 7 is of greater length than the threaded portions of the drill members and presents a threaded socket at its upper end to receive the lower threaded portion of a drill-stock 8, which may be of the usual or any preferred construction.

By having the drill members approximately keystone-shaped when combined or assembled, as shown in Fig. 2, a bore 9 will be presented through which the dislodged material will find egress to the drill-stock and thence outward. In order to prevent the formation of a core that would operate to close the bore 9 under the operation of the drill, at least one of the drill members has its cutting edge projected to and terminated approximately at the center of the bore, as shown at 10 in Fig. 2, and operates in a manner that will be perfectly apparent to secure the above result.

The drill is adapted for use in mining operations or for sinking oil-wells or the like and effects its cutting by impact.

When the drill-points have become dulled from use, they may readily be sharpened, and in the case of the breakage of one of the members its place may readily be supplied, thereby making unnecessary the discarding of the whole drill for this reason.

While the drill has been described as for use in connection with mining-work or well-sinking, it is to be understood that it is not

to be limited to these employments alone, as it may be employed in other positions and for other purposes than those named and still be within the scope of the invention.

5 Having thus described the invention, what I claim is—

A drill comprising a plurality of members all of which have their outer surfaces in the same arc and all but one of which have their 10 inner surfaces in the same arc, the abutting sides of all of the said members diverging at the same angle, said sides extending in radial planes with respect to the drill, each member having a cutting edge extending radially with 15 relation to the drill, all of the cutting edges of

all of the members being in the same horizontal plane, the cutting edge of one of the members extending from the center of the drill to the periphery thereof, and an assembling band constituting a continuation of the drill 20 and having its outer side disposed flush with the like side of the drill.

In testimony that I claim the foregoing as my own I have hereto affixed my signature in the presence of two witnesses.

JOSEPH CUSHING.
